UNITED STATES PATENT OFFICE.

JOHN KIRBY, JR., OF DAYTON, OHIO, ASSIGNOR TO UNITED STATES HEADLIGHT COMPANY, OF BUFFALO, NEW YORK, A CORPORATION OF NEW YORK.

FOCUSING DEVICE.

1,295,528.

Specification of Letters Patent. Patented Feb. 25, 1919.

Application filed August 29, 1918. Serial No. 251,913.

To all whom it may concern:

Be it known that I, JOHN KIRBY, Jr., a citizen of the United States, residing at Dayton, in the county of Montgomery and State of Ohio, have invented a certain new and useful Improvement in Focusing Devices, of which the following is a specification.

My invention relates primarily to electric headlights and has for its purpose to provide mechanism for adjusting the filament of an incandescent lamp to the focal point of a parabolic reflector, as set forth in my previous application, Serial Number 249,383, filed August 12, 1918, and from which my present invention differentiates in certain particulars not described, or claimed therein but which will be made clear in this specification and pointed out in the claims at the end thereof.

In headlights of the type to which my invention is applicable it is essential that the center of illumination be located with accuracy in respect of the focal point of the reflector and to this end my invention consists in the novel construction and combination of parts hereinafter more fully set forth and claimed.

The invention is illustrated in the accompanying drawings, which constitute a part of this specification and in which Figure 1 is a side view, partly in full and partly in section, of a portion of the reflector with the focusing device mounted thereon and showing the stand which supports the rear end of the reflector, and Fig. 2 is a rear view, one half being shown in section through the line A—A of Fig. 1.

Like reference numerals indicate corresponding parts throughout the drawings.

1 represents a portion of the reflector, the front end of which may be mounted upon any suitable slide or base, as 2, in the usual manner, not shown. A ring 3 is secured to the rear of the reflector, the apex of which is cut away at 4 leaving an opening corresponding to the inner diameter of the said ring 3. At the bottom of and preferably integral with the said ring 3 there is a laterally disposed arm or bracket extension 5 having a depending screw threaded member 6, which in conjunction with the standard 7 and nuts 8 and 9 constitute means by which the rear end of the reflector is adjustably supported upon the base 2 as more fully described in my previous application, above referred to. The

free end of the bracket 5 is provided with an interiorly screw threaded boss 10 to receive a corresponding exteriorly screw threaded plug 11 depending from a member 12, having a seat which forms the lower bearing for a spherical element or ball 13, and which, when screwed to place, may be secured against displacement by a pin 14. The bearing member 12 extends upwardly to, substantially, the center of the ball and is provided with an exteriorly screw threaded portion 15 to receive a corresponding interiorly screw threaded portion 16 of a cap 17, the cap being provided with a bearing portion 18 adapted to hold the ball against movement when the cap is screwed down tight and the ball thereby firmly gripped between said upper and lower bearings, which in conjunction with the ball constitutes what is commonly known as a ball joint. At the top of and in vertical line with the center of the ball 13, and preferably integral therewith, there is an exteriorly screw threaded stud 19, which engages an interiorly screw threaded lug or boss 20 depending from a horizontally disposed hollow sleeve 21, and which is prevented from turning thereon by a pin 22. The sleeve 21 carries a longitudinally movable lamp socket holder 23 having a bore 24 through which pass current conducting wires, not shown, leading to the lamp socket 25 and conveying electric current to the lamp filament 26, in the usual manner, the focal point of the reflector being shown at +. The sleeve 21 is provided with an outstanding lug 27, and secured to the rear or free end of the socket holder 23 there is a collar 28 having an extension or arm 29 disposed opposite the said lug 27, the latter being drilled and tapped to receive a regulating screw 30, the reduced shank, 31, of which passes through a smooth bore in the extension 29, and to the outer end of this shank there is secured a hand wheel 32, by which the regulating screw may be turned and the socket holder thereby moved forward or backward according to the direction in which said screw is turned. Interposed between the lug 27 and the extension 29, and surrounding the regulating screw, there is a coiled spring 33, which is retained in place by bosses 34 and 35; the function of this spring being to take up any slack there may be in the threads and thereby prevent undue movement of the said screw and consequent 110

movement of the socket holder, otherwise liable to occur from jars and vibration incident to a moving locomotive or other vehicle.

- 5 The plug 11 is provided with a receptacle 36, within which there is located a coiled spring 37, having one end bearing against the bottom of said receptacle and its opposite end bearing against the ball 13, as shown; the purpose of this spring being to 10 exert yielding pressure on the ball, so that when the screw pressure of the cap is relieved sufficient to permit the ball to move freely in its bearings, the action of the spring will press the ball against the bearing 15 portion 18, of the cap 17, with sufficient force to require slight hand pressure to move the ball, to which a steady movement is thereby contributed during the operation of setting the device.
- 20 Supplementary to the use of the cap 17 as a means of tightening the ball against undue movement, and to provide auxiliary means therefor, the bottom of the plug 11 is drilled and tapped to receive a set screw 38 which 25 passes through the center of the spring 37, and which is provided with a finger piece 39, by which it can be turned to engage the ball in such manner as to materially assist in holding the same secure against undue 30 displacement.

It is to be understood that when the parts are assembled, as shown in the drawings, but little movement will be required to adjust the filament to its proper relation to 35 the reflector, and such movement may be had by a slight turn of the cap 17 and the set screw 38, to relieve the screw pressure on the ball 13 and leave the same free to be moved about in spherical direction, forward 40 and backward movement of the socket holder being obtained, independently of such spherical movement, by turning the regulating screw 30. Then, when the filament is properly adjusted, the ball is permanently gripped by turning the cap 17 and 45 the set screw 38, as hereinbefore explained.

Having thus fully described the construction and operation of my invention as embodying the best manner of carrying out 50 the same I do not wish to be understood as limiting the invention to focusing devices, nor to the specific details shown and described, as it is obvious that the same may be used for other purposes and that its 55 construction as herein detailed may be departed from in various ways without departing from the scope and spirit of the invention.

What I claim and desire to secure by Letters Patent is:

- 60 1. In a focusing device, a bracket carrying a fixed ball bearing, a support for said bracket, a ball located in said bearing, a receptacle having communication with said bearing, a spring located in said receptacle adapted to exert pressure on said ball, an

adjustable cap constituting a movable bearing for said ball and adapted to engage and co-act with said fixed bearing to exert and relieve pressure on said ball, in combination with a lamp socket holder and a support 70 therefor, and regulative means for imparting to said socket holder longitudinal movement independently of said ball.

2. In a focusing device for headlights, the combination with a reflector of a bracket 75 and a support therefor, a fixed ball bearing carried by said bracket, a ball located in said bearing, an adjustable cap constituting a movable bearing for said ball and adapted to engage and co-act with said fixed bearing 80 to grip and release said ball, a receptacle having communication with said fixed bearing, a spring located in said receptacle adapted to exert yielding pressure on said ball, a lamp socket holder and a tubular 85 support therefor carried by said ball, a lug protruding from said tubular support and having a threaded perforation therethrough, an arm fixed to and extending from said socket holder provided with a smooth perforation therethrough, and a regulating screw operative through said perforations 90 whereby said socket holder may be moved forward and backward independently of movement of said ball.

3. In a focusing device for headlights, the combination with a reflector of a bracket and a support therefor, a fixed ball bearing carried by said bracket, a ball located in said bearing, an adjustable cap constituting a 100 movable bearing for said ball and adapted to engage and co-act with said fixed bearing to grip and release said ball, a receptacle having communication with said fixed bearing, a spring located in said receptacle 105 adapted to exert yielding pressure on said ball, a lamp socket holder and a tubular support therefor carried by said ball, a lug protruding from said tubular support and having a threaded perforation therethrough, an arm fixed to and extending from said socket 110 holder provided with a smooth perforation therethrough, a regulating screw operative through said perforations whereby said socket holder may be moved forward and 115 backward independently of movement of said ball, and a spring arranged to reduce tendency to undue movement of said regulating screw.

4. In a focusing device for headlights, the 120 combination with a reflector of a bracket and a support therefor, a fixed ball bearing carried by said bracket, a ball located in said bearing, an adjustable cap constituting a movable bearing for said ball and adapted 125 to engage and co-act with said fixed bearing to grip and release said ball, a receptacle having communication with said fixed bearing, a spring located in said receptacle adapted to exert yielding pressure on said 130

ball, a lamp socket holder and a tubular support therefor carried by said ball, a lug protruding from said tubular support and having a threaded perforation therethrough, an arm fixed to and extending from said socket holder provided with a smooth perforation therethrough, a regulating screw operative through said perforations whereby said socket holder may be moved forward and backward independently of movement of said ball, and auxiliary means for securing said ball against movement in said bearings.

5. In a focusing device for headlights, the combination with a reflector of a bracket and a support therefor, a fixed ball bearing carried by said bracket, a ball located in said bearing, an adjustable cap constituting a movable bearing for said ball and adapted to engage and co-act with said fixed bearing to grip and release said ball, a receptacle having communication with said fixed bearing, a spring located in said receptacle adapted to exert yielding pressure on said ball, a lamp socket holder and a tubular support therefor carried by said ball, a lug protruding from said tubular support and having a threaded perforation therethrough, an arm fixed to and extending from said

socket holder provided with a smooth perforation therethrough, a regulating screw 30 operative through said perforations whereby said socket holder may be moved forward and backward independently of movement of said ball, a spring arranged to reduce tendency to undue movement of said regulating screw, and auxiliary means for securing said ball against movement in said bearings.

6. In a device of the character described, the combination of a single spherical element and a supporting bearing therefor having a depending member, a bracket support for said member, a chamber formed in said member and extending through said supporting bearing, a spring located in said chamber, and a movable block adapted to impinge the surface of said element and to coöperate with said spring to steady the movement of said element.

In testimony whereof, I affix my signature 50 in the presence of two witnesses this 21st day of August, 1918.
